UNITED STATES PATENT OFFICE.

JULES REHAUT, OF DOBBS FERRY, NEW YORK.

BUILDING-BLOCK AND WALL CONSTRUCTED THEREOF.

No. 926,767.

Specification of Letters Patent.

Patented July 6, 1909.

Application filed April 27, 1906. Serial No. 313,912.

To all whom it may concern:

Be it known that I, JULES REHAUT, a citizen of the United States, residing at Dobbs Ferry, in the county of Westchester and State of New York, have invented certain new and useful Improvements in Building-Blocks and Walls Constructed Thereof, of which the following is a specification.

This invention relates to new and useful improvements in building blocks and walls constructed thereof and particularly contemplates a hollow block of novel construction and possessing numerous advantages over the blocks ordinarily employed.

15 A primary object of the present invention is to provide a block which in wall construction will not conduct cold or heat and which shall be free from dampness.

A further object is to provide a block which 20 in assembled relation in wall construction shall present a plane finished surface practically unbroken, the adjacent edges of the blocks abutting one another in contacting relation.

25 The detailed construction will appear in the course of the following description in which reference is had to the accompanying drawings forming a part of this specification, like numerals designating like parts throughout the several views, wherein—

Figure 1 is a perspective view of a block constructed in accordance with the present invention, partly in section, Fig. 2 is an end elevation thereof, Fig. 3 is a transverse section thereof, Fig. 4 is a fragmentary transverse section showing the manner in which two adjacent blocks are joined, and Fig. 5 is a longitudinal section.

In the practical embodiment of my invention I employ a block 1 of substantially U-shape which is closed on three sides and formed with an open top 2. The body portion of said block is hollow and according to the circumstances of its use, may be divided 45 into a plurality of air chambers, a central partition 3 extending vertically from the bottom 4 and dividing the block into air chambers 5, as shown in Fig. 5.

The side walls 6 are formed adjacent to the 50 bottom 4 with depending flanges 7, coextensive with said side walls and formed with beveled inner surfaces 8. Said side walls are formed along their upper edges with similarly constructed flanges 9 adjacent to the inner surface of the block. The flanges 9 are provided with beveled outer edges 10 extending

in the same direction as the beveled edges 8 of the flanges 7. Adjacent said beveled edges 10 a shoulder 11 is formed on each side of the upper side edges of the block. As disclosed in Fig. 2 the ends of the block may be formed with flanges 12 similar in construction and arrangement to the flanges 7 and 9.

Upon reference to Fig. 4, it will be noted that in assembling the blocks to form a wall, the flange 9 and the shoulder 11 upon the one block are seated in interlocking relation upon the flanges 7 of the lowermost block. It is to be noted that the flanges 7 are of greater depth than the flanges 9, so that a space 12 occurs between the wall 4 of the one block and the flange 9 of the adjacent overlying block. The shoulder 11 engages the upper edge of the flange 7 and the beveled edges 10 and 8 of said flanges 9 and 7 about one another throughout their lineal extent. In a wall constructed of my improved block, the joints between the blocks are on the inside thereof, that is in the lower portion of the air chambers 5. As shown in Fig. 4 mortar 13 or any other suitable binding agent spread upon the surface of the wall 4, fills the space 12 before mentioned and effects a sealed inner joint between the adjacent blocks. When the air chambers 5 are sealed, dead air spaces are formed throughout the entire length of the wall, which are practically non-conductors of cold or heat and which resist the penetration of moisture.

Inasmuch as the joint between the blocks is on the inside thereof, the faces of the exposed walls may be highly finished in accordance with the methods practiced in the art to present an ornamental interior or exterior surface. Where it is desired to paper the wall, it is not necessary to employ a plastering or smoothing agent, as the paper may be placed directly upon the smooth and practically unbroken surface of the blocks in their assembled relation. The pressure of the air in the chambers 5 serves to prevent the mortar from rising in said chambers and to spread said mortar to fill the interstices 12.

Having fully described my invention, I claim:

1. In a building block of the character described, the combination of a hollow rectangular body portion of substantially U-shape in cross-section, and comprising a horizontal portion and sides depending therefrom, and provided with upward extensions forming flanges extending longitudinally along the

upper side edges of said horizontal portion, the inner faces of said flanges being beveled and converging downwardly, the said sides having their lower edges formed with longitudinal shouldered flanges of less depth than the said first named flanges, the outer surface of the said last named flanges being beveled and converging downwardly to conformably engage the beveled surfaces of the said first named flanges of the adjacent block, the edges of the said shouldered flanges being thus spaced away from the surface of the horizontal portion of the adjacent block whereby a recess is formed for the reception of a binding agent, substantially as described.

2. In a building block of the character described, the combination of a hollow rectangular body portion of substantially U-shape in cross-section and comprising a horizontal portion and sides depending therefrom having a central transverse partition bridging the same and forming spaced open chambers, and provided with upward extensions form-

ing flanges extending longitudinally along the upper side edges of said horizontal portion, the inner faces of said flanges being beveled and converging downwardly, the said sides having their lower edges formed with longitudinal shouldered flanges of less depth than the said first named flanges, the outer surface of said last named flanges being beveled and converging downwardly to conformably engage the beveled surfaces of the said first named flanges of the adjacent block, the edges of the said shouldered flanges being thus spaced away from the surface of the horizontal portion of the adjacent block whereby a recess is formed for the reception of a binding agent, substantially as described.

In testimony whereof I affix my signature in presence of two witnesses.

JULES REHAUT.
